UNITED STATES PATENT OFFICE

CLARENCE R. PRESSLEY AND FRENCH B. WILLIAMS, OF FORT WORTH, TEXAS

COTTON GIN

Application filed April 16, 1929. Serial No. 355,646.

Our invention relates to cotton gins and more particularly to certain elements or features hereinafter explained; and the object is to provide special rib constructions and means for adjusting the ribs and to provide ribs which can be rigidly attached at one end and which have a construction which will prevent back lash of the cotton, that is, which will prevent the lapping of the lint cotton on the ribs when there is back pressure, the ribs being of such area in cross-section that the lint will not be long enough to wrap about the rib. Another object is to provide ribs which will be rigid to be used in combination with revolving ribs and to meet requirements of gin equipment of certain type on which other ribs cannot be used. Another advantage is the head construction with adjustable means. Other objects and advantages will be fully explained in the following description and the invention will be more particularly pointed out in the claims.

Reference is had to the accompanying drawings which form a part of this application.

Fig. 1 is a side of the gin assembly, the casting being removed.

Fig. 2 is a detail view, illustrating the rib construction.

Fig. 3 is a perspective view of one of the bearing brackets for the gin heads.

Fig. 4 is a plan view of the same.

Fig. 5 is a front view of one of the ribs.

Fig. 6 is a rear view of one of the ribs.

Fig. 7 is a rear elevation of four ribs, partly in section, taken on the line leading from 7 in Fig. 2.

Fig. 8 is a cross-section of a rib, taken on the line 8—8 of Fig. 5.

Fig. 9 is a detail view of the driving gear for the doffing roller and the revolving ribs.

Fig. 10 is a perspective view of a portion of a gin stand, showing the two heads and the manner of connecting the same.

Similar characters of reference are used to indicate the same parts throughout the several views.

The gin stand has a frame of ordinary type, having uprights 1 and 2, horizontal beams 3 and 4 and diagonal braces 5. The

gin stand has side casing members 6 and back member 7. The gin has revolving saws 8 provided with a shaft 9 of the usual form.

The drawings show revolving ribs 10, such as shown in the application of French B. Williams for cotton gins, filed Oct. 17, 1927, Ser. No. 226,616, and also show a doffing roller 11. Driving means are provided for the revolving ribs and the doffing roller. A bearing bracket 12 is rigidly attached to one of the gin heads 13. A sprocket wheel 14 is provided with a shaft 15 which is journaled in the bearing bracket 12. A single sprocket chain 16 drives the doffing roller 11 and the revolving ribs 10 from the sprocket wheel 14. A pulley 17 is made rigid with the shaft 15 for driving this shaft.

The heads 13 are provided with adjustable means for attaching the same to the gin stand. The advantage is that the hinges are not attached to wooden frame members and consequently the weight is taken from the wooden beams. The heads have rear extensions 18 and lugs 19 are formed on these extensions. Adjustable bearing members 20 are mounted on the wooden frame member 21. The members 20 have upright guard members 22. Open-topped bushings 23 are mounted in the guard members 22. The guard members 22 have vertical grooves 24 and the bushings 23 have flanges 25 which rest in the grooves 24. The gin breasts are hingedly connected to the gin stands by the adjustable bearing members. The bearing members 20 are adjustable laterally on the frame member 21. With such provisions, the gin breasts are made more easily cooperative with the ribs of the gins.

On account of the location of certain parts in air blast gins, it has been found to be advantageous to use the kind of ribs herein shown. The ribs 25 are approximately T-shaped in cross-section. Each rib 25 projects between two saws 8. The ribs 25 are constructed for strength and each rib has a forked lower end. The fork is arcuate in form and is adapted to engage the end and part of the side of the frame member 26. This arrangement is for bracing purposes. Each rib 25 is secured to the frame member

26 by three screws. Adjacent to the fork or angular portion of the rib, the rib has a lateral brace 27 and the adjacent rib has a cut-out to receive the flange 27. The ribs thus have interlocking connections which are secured to the frame member 26. The ribs 25 terminate in close proximity to the revolving ribs 10 and are curved near the ends, as shown at 28, the object being to start the unginned cotton and the seed upwardly to cooperate with the revolving ribs 10, to form a roll in the roll box. Another advantage in the T-shape of the ribs 25 is that the ribs are wide enough and deep enough to prevent the fibre of the cotton from wrapping on or clinging to the ribs when there is back lash or choking of the passage of the air, either about the gin or the condenser. The ribs are thus kept clear of cotton fibre.

20 The seed cotton is fed to the gins in the usual manner. The fibre is stripped from the seed by the saws and taken away to the condenser (not shown), and the seed fall out of the front of the gin in the usual manner. The 25 effect of the improved rib construction, including both the stationary ribs 25 and the revolving ribs 10, and the doffing roller 14 in cooperation with the saws is to maintain a loose roll of unginned cotton and seed in the 30 roll box instead of a tight roll as in other gins. There is a great advantage in keeping a loose roll. There is not so much friction and the gins gin the cotton much faster.

What we claim, is,—

- 35 1. In a cotton gin provided with a frame and a gang of saws, a gin breast having a pair of heads having rear extensions and journal lugs formed on said extensions, laterally adjustable brackets for said lugs attached to the gin frame and forming bearings for said journal lugs, a cross beam attached to the lower parts of said heads, and ribs attached to said cross-beam and projecting between the saws of the gin and terminating 40 approximately at the ginning point with upward curves and near the periphery of said saws.
2. In a cotton gin provided with a frame and a gang of saws provided with a shaft 50 journaled in said frame; a gin breast having a pair of heads pivotally connected to said frame, revolving ribs provided with a shaft journaled in said heads, a cross beam attached to the lower parts of said heads and provided with an acuate upper edge, and ribs provided with angular recesses in their ends conforming to the contour of said edge and attached thereto and projecting between the saws of the gin and terminating with 55 upward curves in close proximity to the peripheries of said revolving ribs.
3. In a cotton gin provided with a frame and a gang of saws provided with a shaft journaled in said frame; a gin breast having 60 a pair of heads pivotally connected to said

frame, revolving ribs provided with a shaft journaled in said heads, a cross beam attached to the lower parts of said heads and provided with an acuate upper edge, and ribs provided with angular recesses in their lower ends conforming to the contour of said acuate edge and attached thereto and having bodies T-shaped in cross-section and projecting between said saws and terminating with upward curves in close proximity to said revolving ribs.

4. In a cotton gin provided with a frame and a gang of saws having a shaft journaled in said frame; a gin breast having a pair of heads pivotally connected to said frame, revolving ribs and a doffing roller cooperating therewith and shafts for said ribs and roller journaled in said heads, gearing carried by said head for driving said ribs and roller, a cross-beam attached to the lower ends of said heads, and ribs having interlocking flanges attached to said cross-beam and projecting between said saws and terminating in close proximity to the peripheries of said revolving rollers and cooperating with said revolving ribs at the ginning point.

5. In a cotton gin provided with a frame and a gang of saws provided with a shaft journaled in said frame; a gin breast having a pair of heads pivotally connected to said frame, a rail attached to the lower ends of said heads, revolving ribs provided with a shaft journaled in said heads, said ribs running slightly between said saws, and stub ribs attached to said rail and projected between said saws and terminating with upwardly curved ends in close proximity to said revolving ribs and cooperating with said saws at the ginning point for stripping lint from the cotton seed and cooperating with said revolving ribs for forming a roll in the roll box.

In testimony whereof, we set our hands, this 8th day of April, 1929.

CLARENCE R. PRESSLEY.
FRENCH B. WILLIAMS.
